UNITED STATES PATENT OFFICE

2,203,118

AUTOMATIC ELEVATOR

Howard E. Williams, Huntington Park, Calif.

Application January 31, 1938, Serial No. 187,913

4 Claims. (Cl. 294—90)

This invention relates to an automatic elevator for the purpose of raising and lowering pipe casting or tubing in a well such as an oil well.

An object of my invention is to provide an automatic elevator of the two door or jaw type, in which the jaws are automatically moved into closed position and locked in closed position by the movement of the elevator against the pipe or tubing.

10 Another object is to provide an automatic elevator which can be reversed in position so as to engage either the up-set type of pipe or pipe having collars thereon.

Still another object is to provide an automatic elevator of the character stated in which the jaws can be quickly and easily released, for the purpose of disengaging the pipe by means of conveniently placed plungers.

20 A feature of my invention resides in the novel means of transferring the load of the pipe from the gates to the body of the elevator, and another feature resides in the complete encircling of the pipe by the jaws while the pipe is being moved.

25 Other objects, advantages and features of invention may appear from the accompanying drawing, the subjoined detailed description and the appended claims.

In the drawing:

30 Figure 1 is a top plan view of my elevator.

Figure 2 is a transverse sectional view of the same.

Figure 3 is a front elevation of the elevator.

Figure 4 is an end view of the same.

35 Referring more particularly to the drawing, the numeral 1 indicates the body of the elevator, which includes a pair of outwardly extending ears 2, 3, which receive the links (not shown). It is to be noted that the body 1 is symmetrical as to a horizontal plane through the elevator, and by this construction the elevator can be reversed in position for the purpose to be further described.

40 A pair of jaws 4, 5 are pivotally mounted in the body 1 and each jaw is provided with a pipe engaging jaw which is substantially semi-cylindrical in form. Each of the jaws is provided with outwardly extending hubs 6, 7 on the top and bottom thereof, which project over the body 1, and a pin 8 extends through the hubs, and the body, thus pivotally attaching the jaws to the body. The pins 8 are arranged in alignment and are preferably substantially in alignment with the center line of the ears 2, 3, as shown in 45 Figures 1 and 2.

At one end, the jaws 4, 5 are provided with a tapered seat 9 for the purpose of receiving up-set type of pipe, and the other end of the jaws are not provided with a seat, so that the pipe having couplings or collars can be worked upon. Thus, 5 by turning the elevator end for end, it is possible to work upon either up-set type of pipe, or the collar type. Since the body of the elevator is symmetrical on each side of a horizontal plane, through the center of the elevator, this reversing 10 can be accomplished without impairing the strength or effectiveness of the tool. The overlapping hubs 6, 7 of the gates will transmit the load of the pipe directly to the body of the elevator which is designed to carry the entire 15 weight.

From an examination of Figures 1 and 2, it is seen that the jaws 4, 5, when in closed position, will entirely encircle the pipe and these jaws meet on a line at the center of the elevator, 20 thus enabling the jaws to be complementary in shape, and consequently, simple to cast and machine.

The jaws are locked when encircling the pipe by means of a block 10, which is mounted on the 25 body 1 and is yieldably pressed against a shaped seat 11 in each of the jaws. The block 10 is spring pressed into its seat in the jaws, and consequently, the jaws are effectively held around the pipe, and are only releasable by manually 30 operable means, substantially of the following character:

A pair of pins 12, 13 extend horizontally through the body of the elevator and are slidable in said body. Coil springs 14, 15 surround the 35 pins 12, 13, respectively, and bear against the heads of these pins, thus yieldably pressing the pins outwardly to the position shown in Figure 2. An arm 16 extends across the back of the elevator and is pivotally attached to both of the 40 pins 12 and 13. The block 10 is secured to the center of the arm 16, and it will thus be evident that the springs 14, 15 will press the block 10 into its seat as shown in Figure 2.

The block is withdrawn from its seat by pressing 45 either of the pins 12 or 13 inwardly, whereupon the jaws 4, 5 are free to swing outwardly, and release the pipe. A rearwardly extending finger 17 is provided on each of the jaws 4, 5 for the purpose of retracting the block 10, when the 50 jaws are moving into closed position.

As soon as the jaws have closed, the springs 14, 15 will move the block 10 to its seated position.

In the open position of the jaws the block 10 engages the fingers 17 as shown in dotted lines 55

in Fig. 1 to hold both of the jaws in such open position and will thus prevent their accidentally closing.

Having described my invention, I claim:

- 5 1. An automatic elevator comprising a body, said body having a pipe receiving opening therein, a pair of jaws pivotally mounted in the body, each of said jaws being adapted and arranged to partially encircle the pipe, a lock block adapted and arranged to engage both of the jaws in closed position thereof, a pair of pins slidably mounted in the body, an arm mounted on the pins, said locking block being mounted on the arm, and a spring engaging each of the pins, and urging said pins outwardly, whereby the block is urged towards seated position.
- 10 2. An automatic elevator, comprising a body, said body being symmetrically formed above and below a horizontal plane through the center of the body, said body having a pipe receiving opening therein, a pair of jaws pivotally mounted in the body, each of the jaws being adapted and arranged to partially encircle the pipe, hubs on each of the jaws projecting over the body, a pivot pin extending through the hubs and through the body, and lock means engageable with the jaws in closed position thereof, whereby the jaws are held to encircle the work, said lock means comprising a pair of spring pressed pins slidably mounted in the body, and an arm attached to

each of the pins and to a block, engageable with the jaws.

3. An automatic elevator, comprising a body, said body having a pipe receiving opening therein, a pair of jaws pivotally mounted in the body, each of said jaws being adapted and arranged to partially encircle the pipe, a lock block adapted and arranged to engage both of the jaws in closed position thereof, a pair of horizontally arranged pins slidably mounted in the body, an arm mounted on the pins with a lost-motion connection, said locking block being mounted on the arm, and a spring engaging each of the pins and urging said pins outwardly, whereby the block is urged towards seated position.

4. An automatic elevator, comprising a body, said body having a pipe receiving opening therein, a pair of jaws pivotally mounted in the body, each of said jaws being adapted and arranged to partially encircle the pipe, a lock block adapted and arranged to engage both of the jaws in closed position thereof, a pair of horizontally arranged pins slidably mounted in the body, said pins being arranged one on each side of the pipe receiving opening, an arm mounted on the pins with a lost-motion connection, said locking block being pivotally mounted on the arm, and a spring engaging each of the pins, and urging said pins outwardly whereby the block is urged towards seated position.

HOWARD E. WILLIAMS.
